CLAIM

The ornamental design for a snack containment and dispensing apparatus, as shown and described.

DESCRIPTION

FIG. 1 is a perspective view of the snack containment and dispensing apparatus;

FIG. 2 is a side view of the snack containment and dispensing apparatus;

FIG. 3 is side view of the snack containment and dispensing apparatus;

FIG. 4 is a top view of the snack containment and dispensing apparatus; and,

FIG. 5 is a bottom view of the snack containment and dispensing apparatus.

The broken lines in the drawing depict portions of the snack containment and dispensing apparatus that form no part of the claimed design.
